(57) **CLAIM**

The ornamental design for a musical instrument stand, as shown and described.

DESCRIPTION

FIG. 1 is a perspective view of a musical instrument stand, showing my new design;

FIG. 2 is another perspective view of the musical instrument stand viewed from another side;

FIG. 3 is a front elevational view of the musical instrument stand;

FIG. 4 is a rear elevational view of the musical instrument stand;

FIG. 5 is a left side elevational view of the musical instrument stand;

FIG. 6 is a right side elevational view of the musical instrument stand;

FIG. 7 is a top plan view of the musical instrument stand;

FIG. 8 is a bottom plan view of the musical instrument stand;

FIG. 9 is a perspective view of one piece of the musical instrument stand;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is a perspective view of a second piece of the musical instrument stand;

FIG. 17 is a front elevational view thereof;

FIG. 18 is a rear elevational view thereof;

FIG. 19 is a left side elevational view thereof;

FIG. 20 is a right side elevational view thereof;

FIG. 21 is a top plan view thereof; and,

FIG. 22 is a bottom plan view thereof.

The broken lines are employed to illustrate environmental structures and form no part of the claimed design.

1 Claim, 18 Drawing Sheets
